ATTACHMENT PLUG CAP

George B. Benander, Yalesville, Conn., assignor
to The Monowatt Electric Corporation, a cor-
poration of Connecticut

Application October 15, 1932, Serial No. 637,977

1. Claim. (Cl. 173—361)

The present invention relates to attachment plug caps such as are used for connecting an electrical conductor to a plug receptacle and especially to attachment plug caps of the type intended to form a part of a cord set, it being understood that by a cord set is meant a length of cord having a plug cap permanently attached to it at one end, the other end of the cord being attached to or adapted to be attached to some other wiring device. In the manufacture of cord sets, one end of the conductor cord length is permanently attached to the plug cap at the factory.

One object of my invention is to provide an improved construction and arrangement of plug cap which can be manufactured at low cost and wherein the cord is attached to it during the assembling of the contact blades in the base.

A further object of my invention is to provide an improved method of assembling a plug cap with the conductor ends attached thereto.

For a consideration of what I believe to be novel and my invention, attention is directed to the following specification and the claim appended thereto.

In the drawing, Fig. 1 is an exploded perspective view of a plug cap embodying my invention; Fig. 2 is a perspective view of a plug cap showing the contacts attached to the base or body and the conductor connected to the contacts, and Fig. 3 is a transverse sectional view of the construction shown in Fig. 2.

Referring to the drawing, 1 indicates the base or body of the cap which may be molded from suitable insulating material, and 2 and 3 indicate the two contacts carried by the base. Contacts 2 and 3 may be brass or other suitable conducting material and may be formed by a punching operation.

40 Base 1 has a central opening 4 for the passage of the conductor. Inside the base on opposite sides of opening 4, the wall of the base is thickened to provide flat seats or surfaces 5 in which are spaced openings 6.

45 Contacts 2 and 3 are alike. Each comprises a prong 7, a foot 8 which extends at right angles to prong 7, and two spaced projecting fingers 9 which are attached to the outer edge of foot 8 and have serrated or roughened edges 10. Formed integral with foot 8 directly adjacent to prong 7 are two clamping lugs 11 adapted to be bent down from the position shown in Fig. 1 to the position shown in Figs. 2 and 3, wherein they clamp the wires 12 of the conductor 13. 55 Fingers 9 fit into openings 6 and are held therein

by frictional engagement, the roughened or serrated edges biting into the material of the base. Foot 8 rests against seats 5.

In assembling the construction, the end of conductor 13 is passed through opening 4 as shown in Fig. 1, after which the ends of the wires 12 from which the insulation has been removed are placed under the clamping lugs 11. As shown clearly in Fig. 2, the wire is placed under one lug, then extended back of contact prong 10 and around to the front of it and under the other lug. The lugs are bent down on the wires as shown in Figs. 2 and 3 to firmly connect the wires to the contacts and the fingers 9 on the contacts are forced into the openings 6. The 15 operations of bending down the lugs 11 and forcing the fingers 9 into opening 6 may be performed as a single operation. To this end, the base 1 may be located in a suitable fixed support and the contacts may be mounted in a suitable 20 fixture adapted to be moved downward relatively to the support and the base. The contacts are placed in the fixture, the ends of the wires placed under the lugs 11 after the manner already explained, after which the fixture is actuated to force the fingers 9 into opening 6 and at the same time press down the lugs 11. This is a simple operation which can be quickly carried out at low labor cost in that the work may be performed by relatively unskilled help. At 25 the same time, a firm and satisfactory connection is established between the wires and the contacts and between the contacts and the base.

It will be noted that lugs 11 are bent outwardly to overlie the feet and that the wires are 35 passed across the surfaces of the prongs adjacent to opening 4. By this arrangement, the lugs when bent down clamp the conductors directly against the top faces of the feet and draw them tightly against the prongs, thus providing good electrical and mechanical connections.

By providing two spaced fingers 9 which engage spaced openings in the base, I obtain a firm reliable connection between the contacts and the base which is not likely to come loose and which holds the contacts from twisting.

While I have described my plug cap as being adapted especially for use in cord sets, it is to be understood that the invention is not limited thereto necessarily as the plug cap may be assembled with the contacts fastened to the base but without bending down the lugs 11. The lugs may be then utilized by bending them down to attach the wires to the contacts when the

plug is to be put into use. In such a case, the lugs 11 function after the manner of the binding screws provided ordinarily in plug caps.

What I claim as new and desire to protect by Letters Patent of the United States is:

A plug cap comprising a base having a central opening for the passage of conductors and flat seats on opposite sides of the opening and directly adjacent thereto, contacts each having

10 a foot which rests on one of said flat seats and a prong which projects outwardly from the foot

at the side of the foot adjacent to said opening, means fastening the contacts to the base, and clamping lugs integral with each of said feet on opposite sides of each prong directly at the bases of the prongs bent outwardly to overlie the respective foot for clamping conductors to the contacts, whereby conductors may be extended under the lugs and across the surfaces of the prongs adjacent to said openings.

5

GEORGE B. BENANDER.
